UNITED STATES PATENT OFFICE.

WILLIAM BOOTS, OF ATTLEBORO, MASSACHUSETTS, ASSIGNOR TO GUYOT BROS., OF ATTLEBORO, MASSACHUSETTS.

LINK BRACELET.

Application filed June 27, 1924. Serial No. 722,817.

To all whom it may concern:

Be it known that I, WILLIAM Boots, a citizen of the United States, residing at Attleboro, in the county of Bristol, State 5 of Massachusetts, have invented new and useful Improvements in Link Bracelets, of which the following is a specification.

This invention relates to certain new and useful improvements in link bracelets and 10 the primary object thereof is to provide a bracelet which has novel and improved means for enabling the links thereof to be easily and quickly connected and disconnected.

15 The invention further aims to provide connecting means for the links which is of a simple and economical construction and which more specifically causes the connecting means to remain exposed upon removal 20 of the adjacent link so as to facilitate reconnection thereof.

The invention has still further and other objects which will be later set forth and manifested in the course of the following 25 description.

In the drawings:—

Figure 1, is a fragmentary side elevation of a bracelet constructed in accordance with 30 the present invention;

Figure 2, is a section on line 2—2 of Figure 1;

Figure 3, is a section on line 3—3 of Figure 2;

Figure 4, is a section on line 4—4 of Figure 1, and

Figure 5 is a section on line 5—5 of Figure 1.

In proceeding in accordance with the present invention the boxes 1 are provided 40 with the usual backs 2 the latter being preferably integrally connected at their ends 3 to the boxes, while the side edges 4 of the boxes are rolled over into engagement with the backs.

45 The slides embody substantially U-shaped spring members 5, the free ends 6 of which are turned outwardly and are received in openings 7 provided therefor in the sides of the boxes 1.

50 Plates 8 are secured to the U-members 5 by striking out fingers 9 and 10 from the rear end of the plate and effecting clamping engagement of the fingers with the opposite sides of the base or closed ends of the members 5. Coil springs 11 are engaged

between the backs 2 and the plates 8 and at their ends are engaged with the inner ends 12 of the backs 2 and the closed or base ends of the U-members 5. The plates 8, it will be noted, upon expansion of the 60 bracelet links will extend over or across the spaces between adjacent links, thus concealing the sides of the U-members 5.

In order to disconnect the links it is merely necessary to relatively expand same 65 and then press one or both of the spring side arms of the U-members 5 inwardly whereupon the ends 6 thereof are disengaged from the openings 7 of the adjacent link. When thus disconnected, the free 70 ends of the side arms of the members 5 and consequently the ends 6 thereof project outwardly of the box thereof and are freely exposed.

To connect the parts, one end 6 of member 5 is first inserted in opening 7 of the adjacent link, and the opposite arm of the member 5 is then depressed and the end 6 of the latter arm then moved into the companion opening 7 of the said adjacent link. 75

Having thus described my invention, what I claim as new and desire to secure by Letters Patent is:—

1. In a link bracelet, links including boxes having openings in the sides thereof, U-shaped members in the boxes having their free ends turned outwardly and received in the openings of adjacent boxes, plates seated on the members and having fingers struck-out therefrom and engaged with opposite sides of the closed or base ends of the U-members, and coil springs between the plates and the backs of the boxes and engaged at their ends with the bases of the U-members and an end of the boxes, the free ends of the U-members being exposed and projecting outwardly from an end of the box thereof upon disconnection from the box of an adjacent link. 85

2. In a link bracelet, links including boxes having openings in the sides thereof, U-shaped members in the boxes having their ends turned outwardly and received in the openings of adjacent boxes, plates connected to the U-members, and springs for tensioning the members, the free ends of the U-members being exposed and projecting outwardly from an end of the box thereof upon disconnection from the box of an adjacent link. 100

105

110

3. In a link bracelet, links including boxes having openings in the sides thereof, U-shaped members in the boxes having their ends turned outwardly and received in the openings of adjacent boxes, and means for tensioning the members the free ends of the U-members being exposed and projecting outwardly from an end of the box thereof upon disconnection from the box of an adjacent link.

4. In a link bracelet, boxes, spring tensioned slides in the boxes, and a pair of

resilient and relatively compressible parts on each slide insertible in an end of the adjacent link and formed to project outwardly through openings provided therefor in the sides of said adjacent link. 15

In testimony whereof I have signed my name to this specification in the presence of two subscribing witnesses.

WILLIAM BOOTS.
